INVENTOR

UNITED STATES PATENT OFFICE.

JOSEPH W. OURADNIK, OF KEWAUNEE, WISCONSIN.

SNOW PLOW AND ROLLER.

Application filed June 22, 1920. Serial No. 390,729.

To all whom it may concern:

Be it known that I, JOSEPH W. OURADNIK, a citizen of the United States, residing at Kewaunee, in the county of Kewaunee and 5 State of Wisconsin, have invented certain new and useful Improvements in a Snow Plow and Roller, of which the following is a specification.

This invention relates to road machines 10 and more particularly to a snow roller and road grader, the primary object being to provide a machine of this character which may be employed to keep the roads in good condition at all times during the year.

One of the objects of the invention is to 15 provide a machine for rolling the snow on roads and highways so that it will be firmly packed down whereby a firm surface will be provided so that traffic will not be interrupted.

Another object of the invention is to provide a machine of this character which will operate in the manner similar to an ordinary tractor so that a relatively wide surface 20 may be operated on by the machine while it is in use.

The invention further aims to provide a machine of this character which will be provided with power mechanism for moving 25 the machine and which will be so constructed as to permit it to be used while the snow is falling so that the snow may be packed as it gathers on the ground.

Another object is to provide a tractor machine 30 which may be employed as a plow to remove soft snow when desired so that the roads may be cleared when the snow softens and begins to melt.

A still further object of the invention is 35 to provide a tractor machine adapted to be used as a road grader for keeping the surface of the road in proper condition.

The invention also contemplates the provision of means which will co-operate with 40 the tractor to improve the condition of the road surface so that material forming the covering for the road may be kept free from ruts and unevenness and generally improve the surface of the road.

Other objects of the invention will appear 45 upon consideration of the following detail description and accompanying drawings, wherein:—

Figure 1 is a side elevation of the machine

constructed substantially in accordance with 55 my invention,

Figure 2 is a horizontal section taken approximately on the line 2—2 of Fig. 1,

Figure 3 is a vertical longitudinal section taken on the line 3—3 of Fig. 2, 60

Figure 4 is a rear end elevation,

Figure 5 is a vertical transverse section, taken approximately on the line 5—5 of Fig. 3,

Figure 6 is a detail view of a portion of 65 the gearing mechanism,

Figure 7 is a plan view showing a locking device used in connection with the invention,

Figure 8 is a longitudinal section of the 70 same,

Figure 9 is a fragmentary plan view showing a plow adapted for attachment to the machine and

Figure 10 is a perspective view of a brace 75 member adapted to be used with the plow.

Referring to the drawings by numerals, the sub-structure of the machine is adapted to support a housing within which the main mechanism is arranged as generally illustrated in Figs. 2 and 3 of the drawings. The sub-structure comprises longitudinal frame bars 1 preferably I-beams having their forward ends extended upwardly at an angle as indicated at 2. Mounted upon the frame 80 bars 1 are bearings 3 which receive transverse shafts 4 having gear wheels or sprockets 5 mounted thereon. The sprockets are relatively large in diameter and extend below the lower marginal edges of the frame 85 bars 1. Carrier chains 6 are trained over the rearmost sprockets and are engaged by the other sprockets and the chains also engage smaller sprockets 7 journaled in the end portions of the angular ends 2 of the 90 frame bars. Shafts 8 support the sprockets 7 so that a portion of the forward end of the chain is extended upwardly at an angle as shown. Attached to the chains are the transversely extending plates or cleats 9 which 95 have their edges close together but which are separately mounted on the chain so that the tractor thus formed is free to travel when the gears are set in motion. Ordinary cleats are adapted to be mounted in the cleats 100 if desired.

As shown to advantage in Figs. 4 and 5 the tractors consist of two separate units ar-

ranged relatively close together but since they are of the same construction the above description of the mechanism is applicable to both.

5 Standards 10 are mounted upon the frame bars 1 and support a main platform 11 which also forms the flooring for the body of the tractor which supports the driving and operating mechanism. This platform 10 has a large roomy housing built thereon provided with windows arranged in any preferred manner whereby the operators of the tractor may be protected from the action of the elements during inclement weather.

15 Referring particularly to Fig. 2, a gasoline engine 12 is mounted upon the platform and it will be obvious that any type of engine or motor may be employed. A drive shaft 13 from the engine is provided at one 20 end with a beveled gear 14 in mesh with a beveled gear 15 which drives a transmission shaft 16. The shafts 4 for the tractors are independently mounted and are adapted to operate at one side independently of the 25 shafts at the other side. The rearmost shafts 4 are provided on their outer extended ends with sprockets 17 over which chains are trained as indicated at 18 and these chains are engaged with sprockets 19 on the extended ends of counter shafts 20 supported 30 in bearings within the housing. The inner end of each counter shaft 20 is provided with a beveled gear 21 each of which meshes with a beveled gear 22 on the end of one of 35 a pair of auxiliary shafts 23. Each auxiliary shaft is also provided at its opposite end with a small beveled pinion 24 and a larger beveled pinion 25. Slidably mounted driving gears are arranged on the transmission shaft 16 and these include a set of 40 gears for each pair of gears 24 and 25, the larger beveled gear 26 being adapted to mesh with the larger beveled pinion 25 while the smaller drive pinion 27 is adapted to 45 mesh with the smaller beveled pinion 24. The two beveled gears 26 and 27 are connected together in any suitable manner as by a sleeve 28 and this sleeve is slidable on the shaft 16 with the gears 26 and 27 so that 50 when the gear 26 moves out of engagement with the pinion 25, the gears 27 will move into engagement with the pinion 24. This will permit the speed of the tractor shaft to be changed when desired and it will be 55 noted that the arrangement will permit the shafts to be operated in opposite directions for reversing one of the tractors when it is desired to turn quickly. These sleeves 28 are adapted to be operated by suitable levers 60 29 pivoted as indicated at 30 and reaching to a point within convenient reach of the operator of the machine.

With the above mechanism, it will be readily appreciated that the snow on the 65 surface of the roadway may be quickly

rolled and packed so that a firm surface will be provided to assist traffic. The machine may be operated while the snow is falling so that it is firmly packed as it gathers on the ground.

70 The mechanism for using the device as a road grader comprises a scraper blade 31 having a reinforced edge piece 32. This scraper blade is attached to upright supports 33 which are extended through openings in 75 the ends of movable beams 34. These beams are extended longitudinally into the housing and are movable through casings attached to the platform so that longitudinal adjustment of the beams will be permitted 80 whereby the angular positions of the scraper blade may be changed. This is accomplished by providing the beams 34 with rack bars 35 adapted to be engaged by rack pinions 36 and 37. A transverse shaft 38 is provided 85 with a beveled gear 39 in mesh with a beveled gear 40 on a hand wheel shaft 41 which is provided with a hand wheel 42 whereby the shaft may be manually rotated. A gear 43 on one end of the shaft 38 meshes with 90 an intermediate gear 44 on an intermediate shaft 45 and the gear 44 meshes with the rack gear 36, the latter being mounted on a shaft 46. This will cause the right hand beam 34 to move in either direction according to the turning movement of the wheel 42. The opposite end of the shaft 38 is provided with a gear 48 which meshes with the rack pinion 37, the latter being on a shaft 49. In this instance no intermediate 95 gear is provided so that the direction of rotation of the gear 37 will be exactly opposite to that of the gear 36 when the hand wheel 42 is turned in one direction. This will cause the left hand beam 34 to move inwardly when the right hand beam 34 moves outwardly. It will be obvious therefore, 100 that by turning the hand wheel 42, the angular position of the scraper blade 31 may be quickly changed.

110 It is also desirable to have the scraper blade tilted longitudinally at certain times and this is accomplished by moving the supporting standards 33. Each standard 33 is slidably mounted in one end of the corresponding beam 34 and has a rack bar 50 extending longitudinally on its inner side. This rack bar is engaged by a rack gear 51 on a shaft 52 supported in suitable bearings and extending into the housing where its inner end is provided with a hand wheel 53. The gear 51 for each supporting member 33 maintains its relative position with respect to the rack bar by virtue of its engagement therewith but the shaft is keyed to the gear 115 in a manner that will permit longitudinal movement of the gear on the shaft so that the mechanism provided for lifting either end of the scraper blade will not interfere 120 with the mechanism for providing the an- 125

gular adjustment of the blade. It will be obvious that by turning either of the hand wheels 53, either end of the scraper blade may be raised or lowered.

- 5 In Figs. 7 and 8 I have illustrated a mechanism which may be utilized to lock the beams 34 if the lock provided by the engaging gears is not sufficient. This lock comprises a foot pedal 55 tilted as indicated at 10 56 on a pivot and connected to a double pawl 57. The latter consists of a rock shaft 58 having an extension 59 connected as indicated at 60 to the foot pedal while the opposite ends of the shaft have the locking pawls 15 61 adapted to engage the rack bars 35 on the beams so that when the beams are set in the desired position the same may be locked. Obviously any other suitable locking means may be provided for this purpose.
- 20 Figs. 9 and 10 illustrate a plow attachment which may be employed if desired. The sides of the plow are formed of plates or blades 65 hingedly connected as indicated at 66, this hinge forming the apex or point 25 of the plow when it is in use. A brace bar 67 has its ends engaged with the inner surfaces of the plow plates 65 and is held in position by angular connecting cleats 68 adapted to be removed when the plow is to be dis- 30 connected so that the plates 65 may be folded on the hinge connection 66 to be packed in a relatively small space when the plow is not in use. A central brace member 69 is provided which has a connecting bar 70 35 adapted to be removably connected to the upright members 33. A central brace bar 71 extends forwardly from the bar 70 and terminates in a finger 72 adapted to engage the hinge connection 66 so as to provide a firm 40 brace for the point of the plow. It will be understood that the details of this mechanism for connecting the plow may be varied according to the scope of the appended claims.
- 45 It will be noted by referring to Fig. 1 that a coupling link 74 is attached to the rear of the platform. This is for the purpose of providing a coupling for connecting any trailer to the machine and it is 50 pointed out that the invention contemplates the provision of a heavy cylindrical roller weighted down in the manner common to devices of this character so that the roller will assist the tractor in providing a firm 55 surface for the roadway.

From the above it will be observed that

the mechanism includes a very practical and efficient all year road machine and I desire it to be understood that I do not limit myself to the exact details shown and described 60 but prefer to make such changes in the details of construction as fall within the scope of the appended claims.

What I claim is:—

1. In a road machine, the combination of 65 a frame structure, a platform mounted on the frame structure, adjustable supporting beams mounted on the platform, means to manually move the supporting beams independently of each other and means to support the scraper blade from the supporting beams.

2. In a road machine, the combination of 70 a frame structure, a platform mounted on the frame structure, forwardly extending 75 beams carried by the platform and slidably mounted to move forwardly and rearwardly independently of each other, independent operating means for each supporting beam adapted to be manually operated, vertical 80 supporting elements carried by the forward ends of the said beams, a scraper blade attached to the said vertical supports and means to independently adjust the vertical supports to raise and lower either end of 85 the said scraper blade.

3. In a road machine, the combination of 90 a frame structure, a platform supported on the frame structure, supporting beams extended forwardly from the platform and 95 slidably mounted thereon, a rack bar on each beam, and manually operated means to move the said beams in opposite directions when the said manually operated means is actuated and a scraper blade supported from the 95 forward ends of the beams.

4. The combination with a road machine, 100 of a tractor, a platform supported by the tractor, a scraper blade, means supporting the end of the scraper blade to hold the latter edgewise, a rack bar formed on each supporting means, and gears engageable with the rack bars to move the supporting means vertically whereby the opposite ends of the scraper blade may be raised and lowered. 105

In testimony whereof, I have affixed my signature in the presence of two witnesses.

JOSEPH W. OURADNIK.
